UNITED STATES PATENT OFFICE.

RUDOLPH COOPERSMITH, OF MONTREAL, QUEBEC, CANADA, ASSIGNOR, BY MESNE ASSIGNMENTS, TO THE SENG COMPANY, OF CHICAGO, ILLINOIS, A CORPORATION OF ILLINOIS.

DIVANETTE.

Application filed July 1, 1919. Serial No. 307,926.

To all whom it may concern:

Be it known that I, RUDOLPH COOPERSMITH, a citizen of the United States, and resident of the city of Montreal, in the Province of Quebec and Dominion of Canada, have invented certain new and useful Improvements in Divanettes, of which the following is a full, clear, and exact description.

10 This invention relates to improvements in divanettes, and the object of the invention is to provide an article of furniture which may be arranged as a divan or seat in the daytime and transformed into a bed at night.

15 A further object is to provide a device of this character which will accommodate a mattress of standard thickness, thus providing a more comfortable bed.

20 A still further object is to provide a device which may be converted from one form to the other with very little exertion.

Another object is to provide a device in which the bed and seat construction is supported directly on the floor and not on the 25 ends of the divanette.

25 The device consists briefly of a framework supported by casters or the like from the floor and carrying a folding bed bottom and a seat linked up to the bed bottom so as to move automatically into and out of 30 position. The divanette ends are mounted upon the frame and are connected by a back member carrying a movably mounted divanette back.

35 In the drawings which illustrate the invention;

Fig. 1 is an end elevation of the device in folded position, one end being removed to expose the mechanism.

40 Fig. 2 is a view similar to Figure 1 extended to bed form.

Fig. 3 is a partial section on the line 3—3, Figure 1.

45 Fig. 4 is an elevation of the centre connection of the bed.

Referring more particularly to the drawings, 11 designates a frame of suitable construction supported by means of casters 12 or the like on the floor and provided at each 50 front corner with a short upright 13 supported by a brace 14. The frame 11 may be stiffened by braces 15 and the uprights connected toward their upper ends by a cross member 16. A front foot-board 17 is car-

ried by the front frame member 11 and a cross member 16 and extends from end to end of the device. Seat ends 18 of any suitable construction are provided for the divanette or seat and are each provided toward the front vertical edge with an inwardly projecting bracket 19 carrying a suitable number of bullet-pointed pins 20 adapted to engage in the upright 13. At the lower back corner each end is provided with a bracket 21 adapted to be bolted to the frame 11. Each end is thus supported by the frame 11. The ends are connected and held against possible swaying by a seat back 22 provided with a suitable number of tongues 23, which may be secured to the rear vertical edges of the ends by screws or other suitable means. The back 22 carries a narrow top-board 24 held in place by brackets 25 preferably of metal disposed adjacent the ends. At each end of the device, an approximately U-shaped arm 26 is pivotally connected at one end to a bracket 25 and at its opposite end is rigidly connected to a back cushion 27. The shape of the members 26 enables them to clear the top-board 24, so that the cushion 27 may be swung up to the position shown in Figure 2. One at least of the members 26 carries a latch 28 pivoted near its upper end and notched at 29 at its lower end to co-operate with a catch 30 on the bracket 25 when the cushion is in its elevated position, as clearly shown in Figure 2. It will thus be seen that the only load on the ends 18 is their own weight and the weight of the back 22 and cushion 27.

The bed bottom is formed of four sections 31, 32, 33 and 34 pivotally connected one to the other. The section 31, which may be termed the centre connection, is at each side of the bed a rigid T-shaped structure comprising a head 35 and a stem 36 pivoted near its lower end at 37 to the upper end of an upright 13.

The head and stem are held rigidly with respect to one another by a diagonal brace 38. The sections 32 and 33 comprise, at each side of the bed, members 39 L-shaped in cross section and pivoted adjacent their ends to the extremities of the head member 35. The extremities of the members 39 each embrace the head member 35 and the movement of these members relative to the head is thereby limited, so that the members will

swing upwardly relative to the head member 35 but cannot swing downwardly past the horizontal position, as will be clearly seen in Figure 2. The section 34 comprises, on each side of the bed, members 40 similar to the members 39 and connected inside the members 39 of the section 33, so that the section 34 may swing downward from the horizontal position relatively to the members 39 but not upward. The stems 36 of the centre connections 31 are connected across the bed by a member 41 and a similar member 42 is provided at the junction of the sections 33 and 34. These cross members 41 and 42 are located below the plane of the bed bottom sections so as not to form hard unyielding ridges across the bed. To this end the member 42 is carried by brackets 43 depending from the section 33. The remote ends of the sections 32 and 34 are connected across the bed by members 44 and 45. Any suitable type of bed bottom fabric 46 is stretched in the frame formed by the sections 31, 32, 33 and 34 and is preferably one continuous fabric from side to side and end to end of the bed bottom. The head section 32 is provided with a rigid head frame 47 of any suitable construction, having a cross bar 48 at the top terminating in upwardly projecting lugs 49. A folding foot rail 50 of any suitable type is secured to the free extremity of the section 34. The length of the centre section between the points of attachment to the adjoining sections is approximately double the thickness of the mattress which it is intended to use, and the length of the section 33 between its points of attachment to adjoining sections is slightly less than the length of the section 32 between its point of attachment to the section 31 and the head frame, so that the section 33 may be folded upon the section 32. The section 33 is provided at each side adjacent its connection to the section 34 with a lug 51, adapted to rest upon the top rail 48 of the head frame and to be retained by the upturned lug 49.

In order to support the bed bottom in the extended position shown in Figure 2, certain instrumentalities are provided co-operating with the centre connection 31. For convenience, the arrangement at one side only of the device will be described, as both sides are exactly similar. A link 52 is pivotally connected at one end to the frame 11 and at the other end has pivotal and sliding connection in a slotted bracket 53 secured under the free extremity of the section 32. A link 54 is pivotally connected at one end to the stem 36 of the centre connection about midway between the head and the pivot 37. This link has sliding and pivotal connection at its opposite extremity with the link 52. These members support and control the movement of the section 32. A cross arm

55 is rigidly connected to the stem 36 on the opposite side of the pivot 37 from the head 31 and is supported by a bracket 56. The extremity of this cross arm adjacent the bed foot is pivotally connected to a bracket 57 secured to the under side of a seat frame 58 adjacent the front edge thereof. A short leg 59 is connected to the rear corner of the seat frame and is provided with a supporting member 60. This leg is adapted to extend to the floor and support the rear edge of the seat frame in the position shown in Figure 2, the front edge being supported ultimately by the frame 11. A short link 61 is pivotally connected between the seat frame 58 and the bed bottom section 33 as close as possible to its footward end, thus virtually supporting the footward end of the section 33 and the headward end of the section 34. A link 62 is connected between the rear edge of the seat frame 58 at a point on the bed bottom section 34 toward the foot. It will thus be seen that each of the sections 32, 33 and 34 is provided with a double support, while the section 31 is supported directly by the rigid frame. The headward extremity of the cross arm 55 is connected to one end of a spring 63, the opposite extremity of which is connected to the frame 11, the spring serving to assist both in the opening and closing of the bed. A seat cushion 64 is mounted on the frame 58, which also carries at its rear edge a suitable number of stops 65 for the lower edge of the back cushion 27.

Assuming the device to be in the folded seat forming position shown in Figure 1, it may be converted to a bed by first pulling forwardly and upwardly on the lower edge of the back cushion 27 until the cushion swings to the position shown in Figure 2, where it is held by the latch 28 engaging the catch 30. The operator then grasps the foot cross rail of the bed, thus exposed immediately under the top-board 24, and pulls forwardly and upwardly on the same. The spring 63 at each side supplements this pull and swings the centre connection 31 from the position shown in Figure 1 to the position shown in Figure 2, so that the section 33 is carried upwardly and outwardly and eventually inverted to occupy the position shown in Figure 2. Toward the latter part of this movement the spring reaches its maximum contraction and during further movement tends to resist a sudden straightening into line of the sections 33 and 34 and a sudden dropping of the seat cushion 64. As the section 33 pivots around the section 31 and the section 34 pivots around the section 33, a combined action is exerted on the seat frame 58, moving it away from the section 33 upon which it previously rested until it occupies the position shown in Figure 2. As the centre connection 31 swings up, it raises one end of the section 32 and also

draws up the link 54, which operates the link 52 to raise the head end of the section.

To convert the device from a bed to a seat, the foot cross member 45 is raised. The sections 34 and 33 remain relatively rigid for a time and the two swing up from the centre connection 31. Early in this upward swing, tension is exerted through the link 62 and seat frame 58 on the cross arm 55, so that the centre connection 31 gradually swings down toward the position shown in Figure 1, thus lowering the footward end of the section 32 and allowing the links 52 to lower the head end of the section. This movement is at first assisted by the spring 63. When the movement is partially complete, the tension in the seat frame 58 and link 62 is increased owing to the seat frame swinging about an entirely different centre from the section 33, and at the same time a strong thrust is exerted through the link 61, so that the sections 33 and 34 swing relatively to one another, the section 33 folding down over the section 32 and the section 34 assuming a vertical position against the back 22. As the centre connection 31 swings to the position shown in Figure 1, the footward extremity of the arm 55 swings up thus raising the front edge of the seat frame into position. The relative movement of the sections 33 and 34 acts through the links to force the seat forward relatively to the section 33 until it assumes a slightly inclined position, resting at its rear edge upon the down folded section 33 and passing in front of the cross bar 42. The brackets 53 of the section 32 eventually come to rest on the frame 11 and the lugs 51 of the section 33 come to rest on the cross bar 48 of the head frame, so that a rigid support is obtained for the rear edge of the seat. The back cushion 27 is now supported with one hand and slightly raised so that the latch 28 may be disengaged from the catch 30 and the cushion lowered into a position of rest against the stops 65 carried by the seat frame. If it is desired, the back cushion 27 may be lowered, while the device is arranged as a bed, and will come to rest on the mattress forming a conveniently inclined back rest or head rest.

The feature of hanging the ends 18 and back 22 on the bed frame in place of hanging the bed frame between the ends is a point of very considerable importance. The bed is supported directly on the floor, and constant operation of the device will never have the effect of loosening the connection between the bed and the lounge ends and causing the device when arranged as a divanette or seat to be loose in the joints and wobbly. The arrangement also presents a very considerable advantage to both dealers and customers in assembling the structure after transportation or storage. The bed

proper is a unit in itself and the back carrying the cushion 27 and the ends 18 may be removed without affecting the bed in any particular. The device is shipped and stored in this knock-down condition and when assembly is desired, it is only necessary to slip the pins 20 of the ends into the frame members 13 and bolt the brackets 21 in place. This operation is extremely simple, owing to the fact that the bed frame is self-supporting and does not require blocking up or holding in proper position for connection with the ends. When the ends are in place the back is slipped between them and secured by means of the lugs 23. The operations of extending and folding up the bed require no skill on the part of the operator as the seat and springs 63 virtually direct the movement, so that it cannot be improperly carried out. The distribution of weight, combined with the assistance rendered by the springs, is such that very little more than an initiating movement is required to operate the device. The provision of the wide centre connection 31 between the bed bottom sections 32 and 31 provides sufficient room for the doubling of a full thickness mattress.

Having thus described my invention, what I claim is:

1. In a device of the class described, a frame work adapted to be supported on the ground, a folding bed carried by said frame work, a seat frame including seat ends, a connection between the frame work and each of the ends, comprising an apertured member carried by one of the parts, a pin bearing member carried by the other part having the pins thereof adapted to enter the apertures of said member, and a bracket on one part connectible to the other part to hold the pin bearing member in engagement with the apertured member.

2. In a device of the class described, a base frame provided with uprights at the forward corners thereof, and a folding bed thereon comprising a center section pivotally mounted on said uprights, an intermediate section hingedly connected to the center section, a foot section hingedly connected to the intermediate section, and a separate jointed connection between the foot section and the center section spaced from the intermediate section for supporting and folding the foot section.

3. In combination with a device according to claim 2, links pivotally connected between the jointed connection and the intermediate section for supporting and folding the latter.

4. In combination with a device according to claim 2, legs carried by the jointed connection for supporting the foot section.

5. In a device of the class described, a bed bottom comprising a rockably mounted

centre section, a head section and an intermediate section hingedly connected to opposite edges of the centre section and a foot section hingedly connected to the intermediate section, and a toggle between the foot section and the centre section, connected to the centre section on the opposite side of its point of support from the bed bottom and operatively connected with the intermediate section and operative to produce relative movement between the intermediate and foot sections upon straightening of the toggle connection, the arrangement being such that movement of the foot section is operative through the toggle connection to rock the centre section.

6. In a device of the class described, a base frame and a folding bed thereon comprising a pair of side frames each including a T-shaped centre section pivotally mounted adjacent the extremity of its stem on the base frame, side rails pivotally connected to opposite extremities of the T-head and foldable only away from the T-stem 25 one of said rails including a part foldable relatively to the other part and only toward the T-stem, a cross arm rigidly secured to the T-stem at its extremity, a toggle connection between one extremity of said arm 30 and the rail part foldable toward the stem and a connection between said toggle connection and the rail part foldable away from the stem.

7. A sofa bed comprising a frame and a folding bed carried thereby including a center section pivotally mounted on the frame, movable sections foldably connected at the ends of said center section, a rigid upright head frame carried by the outer end of one 40 of said sections, and lugs carried by the other of said sections adapted to be supported on said head frame to hold the sections spaced apart in the folded position of the bed.

45 8. In a device of the class described, a frame, a seat, a foldable bed bottom, a link structure including a single lever at each end for pivoting the seat to swing forwardly and downwardly in overturning, a bed bottom 50 supporting stem at each end to which the levers are rigidly connected, and a pair of links at each side of the frame having a lost motion connection and pivoted to the stem for raising one of the bed bottom sections when the seat is overturned.

9. In a device of the class described, a frame, a seat therefor, a foldable bed bottom, a single lever at each end of the seat pivoted intermediate their ends to the frame 60 and pivoted at the ends to the seat so that the seat will be advanced when inverted in front of the frame and raised thereby when returned to its position as a seat, and bed bottom operating means including stems to 65 which the levers are fixed.

10. A device according to claim 9, in which the bed bottom includes hingedly related head and centre sections, the latter being rigidly connected to said levers and the former being flexibly connected to said levers by the operating means comprising levers connected between the frame and head section and links connecting the first and second mentioned levers.

70 11. In a device of the class described, a frame, an invertible seat, a foldable bed bottom, T-shaped levers each rigidly connected at one end of the tail to said bed bottom and pivotally connected at an intermediate point of the tail to the frame, and pivotally connected at one extremity of the head to said seat.

80 12. In combination with a device according to claim 11, elevating links connected between the frame and bed bottom and operating links therefor connected between said links and the stems of the T-levers.

85 13. In a device of the class described, a frame, a bed bottom comprising articulated head and centre sections, stems rigidly connected to the centre section and supporting the same in pivotal relation to the frame, links pivotally connected between the frame and the head section, and links pivotally connected between said stems and the first 90 named links.

95 14. In a device of the class described, a frame, a bed bottom comprising centre and intermediate articulated sections, stems rigidly connected to said centre section and supporting the same in pivotal relation to the frame, arms rigidly connected to said stems, an invertible seat pivotally connected between the extremities of said arms, and links pivotally connected between the seat 100 and the intermediate section remote from said stems.

105 15. In a device of the class described, a bed bottom including centre, intermediate and foot sections hingedly connected, a frame in pivotal relation to the centre section, an invertible seat pivotally related and connected to the centre section, links connecting the seat and foot section, and links connecting the seat and intermediate section, 110 said seat and links forming a toggle mechanism controlling the relation of the intermediate and foot sections.

115 16. In a device of the class described, a frame, an invertible seat and an articulated bed bottom both pivotally related to said frame and supported thereby, said bed bottom including intermediate and foot sections, feet connected to said seat to support the same in inverted position, links pivotally connected to the feet and to said foot section approximately midway of its articulated and free edges, links connected between the seat and the intermediate section, said links forming means to invert and revert the 120 130

seat and to fold and unfold the intermediate and foot sections relatively to one another upon movement of the foot section.

17. In a sofa bed, a frame provided with 5 uprights at the forward corners thereof, a folding bed comprising a center section pivotally mounted on said uprights, a head section, an intermediate section hingedly connected to the center section, a foot section 10 hingedly connected to the intermediate section, and a separate jointed connection be-

tween the foot section and the center section comprising a seat frame at a distance below the intermediate section having a hinged connection with the center section and supported from the floor when inverted and a link pivotally connecting the outer end of the seat frame and the foot section for supporting and folding the latter. 15

In witness whereof, I have hereunto set 20 my hand.

RUDOLPH COOPERSMITH.
